US00D561347S

(12) **United States Design Patent** (10) **Patent No.:** **US D561,347 S**
(45) **Date of Patent:** **** Feb. 5, 2008**

(54) **PIPETTE WITH PARTICULATE CARRIERS THEREIN**

(75) Inventor: **Hideji Tajima**, Matsudo (JP)

(73) Assignee: **Universal Bio Research Co., Ltd.**,
Matsudo-Shi, Chiba (JP)

(**) Term: **14 Years**

(21) Appl. No.: **29/277,778**

(22) Filed: **Mar. 9, 2007**

(30) **Foreign Application Priority Data**

Sep. 13, 2006 (JP) 2006-024504

(51) **LOC (8) Cl.** **24-02**

(52) **U.S. Cl.** **D24/222**

(58) **Field of Classification Search** D24/112,
D24/222; 422/81, 100, 101, 104, 919, 922,
422/924; 73/863.32, 864.02, 864.09, 864.11,
73/864.14, 864.18

See application file for complete search history.

(57) **CLAIM**

The ornamental design for a pipette with particulate carriers therein, as shown and described.

DESCRIPTION

This application is related to the following applications: U.S. patent application Ser. No. 29/277,775, filed on Mar. 9, 2007, which claims priority to Japanese design application no. 2006-24503, filed on Sep. 13, 2006; U.S. patent application Ser. No. 29/277,779, filed on Mar. 9, 2007, which claims priority to Japanese design application no. 2006-24505, filed on Sep. 13, 2006; and U.S. patent application Ser. No. 29/277,780, filed on Mar. 9, 2007, which claims priority to Japanese design application no. 2006-24527, filed on Sep. 13, 2006, all of the disclosures of which are incorporated herein by reference.

FIG. 1 is a perspective view of the pipette with particulate carriers therein showing my new design;

FIG. 2 is a front elevational view thereof, the rear elevational view being a mirror image;

FIG. 3 is a left side elevational view thereof;

FIG. 4 is a right side elevational view thereof;

FIG. 5 is a top plan view thereof, the bottom plan view being the same; and,

FIG. 6 is a sectional view thereof.
